United States Patent Office.

LEANDER RODNEY, OF NEW YORK, N. Y.

Letters Patent No. 67,586, dated August 6, 1867.

IMPROVEMENT IN PRINTING-PRESSES.

The Schedule referred to in these Letters Patent and making part of the same.

Be it known that I, LEANDER RODNEY, of the city, county, and State of New York, have invented certain new and useful improvements in Machinery for Printing, by which I am enabled to print in any desired number of colors, limited only by the number of forms used; and I do hereby declare and describe my said invention, referring to the accompanying drawings that illustrate this description, in which—

Figure 1 is a perspective view of my printing machine.

Figure 2 is a longitudinal vertical section.

Figure 3 is an end view.

Figure 4 is a transverse section.

Several devices have heretofore been essayed to print in a variety of colors, which, in my judgment, lack the requisite of expedition and accuracy. To obviate these defects is the object of my invention, the construction of which is as follows:

In that arrangement of my invention where the beds for the types or cuts are placed on a right line they should be placed in two rows, as seen at F in the drawings. Over these beds I cause certain cylinders, E, that I denominate impression-cylinders, to pass, impelled by an endless chain, band, or other gearing. Each of these cylinders E carries with it a sheet of paper, the front edge of which is held thereto by means of forceps, grippers, or fingers, as in the Napier and other like presses that are well known and need no description, its rear edge being held by similar forceps. The paper, as the cylinder advances, receives an impression from the form by being pressed on it by the cylinder. In order to insure the proper revolution to the cylinder in passing over the form, and thus prevent slurring, &c., I affix cog-wheels to each end thereof, that gear into stationary racks B on the sides, there being guide-rails on which the cylinders run. These impression-cylinders should be used in pairs, so as to counterbalance each other, or they must be otherwise counterbalanced in all positions, so as to produce an equal strain on the driving-power. Between the forms on each line there must be a space sufficient to receive the inking-rollers, which are caught by the apparatus that drives the cylinders forward, and are thereby carried over the form. When they arrive at the end of the form they descend into the recess between the forms, and are, after the passage of the impression-cylinders, either returned back by springs or other mechanism, or pass under the beds to their former position. Each form has its own separate inking apparatus, and each inking apparatus may use a different color. If the sheet is to be printed on both sides an opportunity is offered for doing so at the end of one line of beds or forms, as the impression-cylinder passes from one series of beds to the other, by one edge of the sheet being released from the forceps or other holder and wrapped around the cylinder in the opposite direction as the revolution of the cylinder is reversed. When great speed is desired in printing large editions I place the lower line of forms upside down and run the impression-cylinders under them. In this case the racks and guide-rails are above instead of below the impression-cylinders, and the cylinders are held up to the forms by means of wheels affixed to the ends of the axis of each cylinder, that run on rails or ways that can be raised or lowered by screws, levers, or other mechanical device to produce the proper pressure for an impression. The ends of the cylinders are governed by guide-rails, as seen at X, that keep them steadily in place.

It is noticeable that I can have as many impression-cylinders as I desire, as the inking apparatus of each is apart from and independent of the others, by which I secure as great rapidity of execution in printing with several colors as has heretofore been done with one; while if I throw off the sheet at each revolution and feed in another, I can secure all the advantages of the "lightning presses," so called.

The ink-fountains and distributors may be so nearly like those found most efficient now in use, and well known to the practical man, as to need no description or illustration, the most important feature being that there may be a dozen or more inking-rollers to each form, attached to endless chains, bands, or other suitable contrivance, leaving a sufficient space for the impression-cylinder to press the sheet on the form while passing over it, the inking-rollers being taken up by the impression-cylinder movement and carried over the form, and released, while the cylinder passes on to the next form.

Having thus fully described my improvements in color-printing and other printing-presses, what I claim as new, and for which I desire to secure Letters Patent, is—

The combination herein described, consisting of the rotating impression-cylinders advancing continuously in one direction, counterbalanced and passing over a series of stationary forms placed in right lines in two rows, one over the other, substantially as and for the purposes herein set forth.

LEANDER RODNEY.
